UNITED STATES PATENT OFFICE.

ABRAHAM A. SOLOMONS, OF SAVANNAH, GEORGIA.

IMPROVEMENT IN MEDICAL COMPOUNDS.

Specification forming part of Letters Patent No. **204,629**, dated June 4, 1878; application filed
February 26, 1878.

To all whom it may concern:

Be it known that I, ABRAHAM A. SOLOMONS, of Savannah, in the county of Chat-
ham and State of Georgia, have invented a
new and useful Composition of Matter, which
is fully described in the following specifica-
tion.

This invention relates to that class of com-
pounds which are to be used in the treatment
of various forms of disease; and it consists
of a composition formed by mixing with the
oil extracted from the saw palmetto (*Sabal
serulata*) sugar-of-milk, in the proportions of
one of oil to seven of sugar.

In the preparation of this remedy the ber-
ries are placed in any suitable device in which
they can be pressed while cold or in their
natural condition. The product thus obtained
is placed in any suitable vessel, where it is al-
lowed to stand until the oily matter has sepa-
rated from the saccharine portion of the ex-
tract, when the oil is drawn off, and is com-

bined with the sugar-of-milk in substantially
the proportions above named.

In administering this remedy it will be
found that, say, thirty (30) grains, for adults,
will be a proper dose, to be used according to
circumstances, and that for children one-half
that amount will be sufficient.

What I claim, and desire to secure by Let-
ters Patent, is—

A composition of matter consisting of the
oil of the berries of the saw palmetto, ex-
tracted by pressure, and sugar-of-milk, in
about the proportions of one of the oil and
seven of the sugar, substantially as set forth.

In testimony that I claim the foregoing as
my own I affix my signature in presence of two
witnesses.

ABRAHAM A. SOLOMONS.

Witnesses:

A. H. ABRAMS,
J. J. ABRAMS.
